UNITED STATES PATENT OFFICE.

FRANK L. EMERSON, OF MOUNTAIN VIEW, CALIFORNIA.

TRACTION-MOTOR.

No. 872,648.

Specification of Letters Patent.

Patented Dec. 3, 1907.

Application filed January 18, 1907. Serial No. 352,929.

To all whom it may concern:

Be it known that I, FRANK L. EMERSON, citizen of United States, residing at Mountain View, in the county of Santa Clara and State of California, have invented new and useful Improvements in Traction-Motors, of which the following is a specification.

My invention relates to a device which I have called a "traction motor".

10 It consists in the combination of mechanism and in details of construction which will be more fully explained by reference to the accompanying drawings, in which—

Figure 1 is a side elevation of my apparatus. Fig. 2 is a section taken through X—X of Fig. 1 and looking to the front. Fig. 3 is a plan view of my apparatus. Fig. 4 is a top view of front gear wheel and clutch. Fig. 5 is a vertical section of the gearing of 20 one front wheel. Figs. 6 and 7 are similar views of the rear wheel transmission. Fig. 8 is a diagrammatic view of the steering mechanism.

It is the object of my invention to provide 25 an apparatus mounted upon wheels carrying its own motor, having connections by which power may be applied to drive each of the wheels; means by which a forward drive may be applied to all of the wheels; means 30 by which the drive mechanism may be reversed without reversing the motor, and means by which the reversed motion may be applied to one or more of the wheels, and the forward drive of the other wheels disengaged.

35 A is the rear and B the front portions of the frame. These frame sections may be made of channel or angle iron of any suitable or desired form. The front section is supported upon a pair of wheels C, the rear portion of the rear section is supported upon wheels D. These wheels are all turnable loosely upon their spindles, as is well shown at 2, in Fig. 2. These spindles are extended and have upturned portions 3 at substantially right angles with the horizontal portion upon which the wheels turn. Surrounding the upturned shafts 3 are sleeves 4, which are fixed to the frame sections to which they appertain, and the drive mechanism is applied to and through the sleeves as follows: The interior peripheries of the wheels have gear teeth 5, and upon the upper ends of the sleeves 4 are wheels 6 having teeth adapted to engage with the

teeth 5 of the bearing wheels. Any desired 55 or well known form of gear teeth may be used in this connection. I have here shown what are known as crown gear, having rounded teeth which will engage with the corresponding teeth of the bearing wheels. 60

The connection between the wheels 6 and the sleeves 4 is effected by means of a suitable form of clutch capable of acting in one direction and releasing to turn freely in the opposite direction. Such a clutch I have 65 shown at 7, Fig. 4, in which balls or rollers are contained in pockets in the hub or interior portion of the wheels 6, and the pockets are wide enough at one end to allow the gear to turn freely with relation to the sleeve 70 in one direction, but to bind when turned in the other direction so that the sleeve and wheel will turn together. This being a well known form of clutch and not claimed as novel. 75

Upon the sleeve and as shown at present beneath the wheel 6 is a beveled pinion 8 which is engaged by a corresponding pinion upon a horizontal shaft 9 which is journaled across the front portion of the frame B; and when this shaft is revolved in one direction it will cause the clutches 7 to engage with the sleeves 4, thus revolving them, and through the toothed wheels 6 to drive the bearing wheels C. If for any reason it is desired to 85 reverse the movement of the apparatus as will be hereafter described, it will be seen that when the machine is backed, these clutches will be released and allow the bearing wheels C to turn, idle power being applied only to the rear wheels to cause the 90 machine to travel backward.

Upon the shaft 9 is fixed a beveled gear 10, and this is engaged by a similar gear 11, which is mounted upon a shaft 12 extending 95 horizontally from end to end of the apparatus. This shaft 12 passes through a sleeve 13 which is carried at the junction of the frames A and B; and this sleeve being rigidly fixed to one part of the frame as A, the other portion B is so connected as to be turnable about the longitudinal axis of the shaft 12. This allows the front wheels C and the rear wheels D of the machine to accommodate themselves to irregularities of the surface 100 over which they are traveling without any strain upon any portion of the machinery, as will be readily seen.

- The shaft 12 is properly journaled upon both frames. Above this shaft I have shown a motor 13 which may be of any desired description. In the present case I have indicated a double opposed horizontal engine mounted transversely of the frame A and the crank-shaft 14, of this engine enters a gear case 15 within which are suitable transmission gears engaging similar gears upon the shaft 9, thus transmitting motion to drive said shaft in a direction which will propel the intermediate mechanism and thus drive all four of the wheels C and D in a forward direction.
- If it is desired to reverse the car, it is effected by means of the usual intermediate sliding gear set, which is operated by a lever 16, so that the direct driving gear may be disengaged and an intermediate gear thrown into mesh to reverse the motion of the shaft 12. The motion of this shaft is transmitted to the rear-wheel shaft 9^a by a beveled gear 10^a from the driving shaft 12. The power from this shaft is transmitted through the toothed wheels 6 to the internal gears of the bearing wheels D in the same manner as has been described for the front wheels; but in order to drive these wheels 6 in either direction, I have shown two sets of ball-clutches 7 similar to those previously described. The upper set 7 are so constructed in the ball pockets, that when the shaft is being driven so as to apply motion to all the wheels in a forward direction, these balls will engage with the sleeves 4 as previously described. Below these, is another set of ball cases as at 7^a, and these are set in the reverse direction so that they will engage the parts to be driven when the shaft 12 is turned in the opposite direction. In order to allow this to be done without interfering with the upper clutches 7, these upper clutches must be disengaged, and this disengaging is effected by means of a turnable disk 17, which is mounted axially with the shaft 3, and which has pins 18 projecting downwardly into the line of path of the balls 7, so that by turning this disk, the pins will push the balls into the wider portions of their pockets, thus disengaging them so that they have no effect in turning the toothed wheels 6 and the clutch balls 7^a located below and acting in the opposite direction, will engage and turn the disks in the opposite direction, thus reversing the motion of one or both of the rear wheels D. It will be found that the reverse movement can be effected by the use of only one of the bearing wheels, which may sometimes be found possible.
- The disk 17 has notches formed on its edges as shown at 19, and a spring pawl 20 carried upon the toothed-wheel 6 is so disposed that when the disk has been turned to disengage the upper clutch, as previously described, this latch will fall into one of the

notches and hold the upper clutch out of engagement. The latch may be disengaged to allow the parts to turn with relation to each other so that the upper clutch may be in engagement again for the forward motion by means of a tooth 21 projecting so that on the commencement of the forward motion which will be effected by the propulsion of the forward wheel C, the turning of the disk will move this tooth so as to disengage the spring pawl 20 and allow the toothed wheel 6 to resume its normal position with the front driving clutch in engagement.

Steering may be effected in various ways. In Fig. 8 I have shown a device in which a vertically disposed steering post 22, (also shown in Figs. 1 and 3) has a steering wheel 23 upon the upper end. At the bottom is a drum 24 around which may be coiled one or two turns of a rope or cable 25. The front end of this cable passes around a similar drum 26 carried upon the front portion of the frame so that by turning the hand-wheel, motion is transmitted to turn this drum 26. Around this drum is coiled another cable 27, each end of which connects with an arm 28 which projects from the steering knuckles, so-called, of each of the forward wheels C. Thus by turning the hand-wheel in one direction, the cable 27 will be caused to coil around the drum 26 and will pull upon one of the crank-arms or levers 28.

A rigid bar 29 extends between these two crank-arms or levers, and the pull upon the cable pulling upon one of the levers, acts through this rigid arm to push the other one, thus turning both of the front wheels so that steering may be effected. As the front and rear frames A and B are turnable with relation to each other, I have shown an idler pulley 40 mounted upon a yielding spring 41, and the cable 25 passing beneath this pulley will yield to conform to the tilting of the frames.

This apparatus may be employed for various purposes. When employed for orchard, or farming work, as is illustrated in the present construction, it is sometimes found desirable to turn the front wheels and the hind wheels in opposite directions so as to make a short turn; this is effected by means of two crank arms 30 connecting from a steering knuckle diagonally opposite of the front and rear wheels and connecting these crank-arms by a rigid rod 31, so that motion may be transmitted from the front steering mechanism to one of the rear wheels, and this is transmitted to the other rear wheel by means of a rigid bar 32 connecting the crank-arms 33 which actuate the steering knuckles. In some cases it may be found desirable to operate the front and rear steering independently, in which case I have shown a second steering wheel 34 mounted upon a steering-wheel shaft 35 near the rear of the machine.

By disengaging the bar 31 this rear steering wheel may serve to actuate the rear steering mechanism independently of the front.

Having thus described my invention, what I claim and desire to secure by Letters Patent, is—

1. In a traction apparatus, a frame, wheels turnable upon axles at the front and rear, said wheels having internal gear teeth around their peripheries, a motor carried upon the frame, and mechanism between the motor and said wheels whereby the wheels may be driven independently, said mechanism comprising gears engaging the teeth of said wheels and mounted on vertical axes.

2. In a traction apparatus, the combination of a main frame, rear wheels journaled and independently turnable thereon, a front frame having a pair of wheels journaled and independently turnable thereon, a longitudinal central connection between the front and rear frames whereby the two are turnable independently about a longitudinal axis, a motor carried upon the frame, and connections between the motor and said wheels for operating the latter, said connections comprising internal gear teeth around the peripheries of the wheels and a vertically-journaled gear wheel for each wheel engaging the teeth of the latter.

3. In a traction apparatus, the combination of front and rear frames having bearing wheels, said wheels having gear teeth around their peripheries, a sleeve fixed horizontally to one of said frames and having a turnable connection with the other, a motor upon the main frame, a counter-shaft passing through said sleeve, means for driving said shaft from the motor, a transverse shaft journaled on the forward frame and means whereby said shaft is driven from the counter-shaft, a vertically-journaled shaft at each end of the transverse shaft, having a gear wheel to engage the teeth of the adjacent bearing wheel, and connections between the ends of said counter-shaft and the vertical shafts.

4. In a traction apparatus, main and supplemental frames connected and turnable about a horizontal centrally located sleeve, bearing wheels having internal gear teeth around the peripheries, vertically journaled gears engaging the teeth of the wheels, a transversely journaled horizontal shaft, gears whereby motion is transmitted from said shaft to turn the wheels, driving gears, a longitudinally journaled countershaft passing through the joint connections of the frames, beveled gears whereby motion is transmitted to the transverse shaft, and motor connections to drive the countershaft.

5. In a traction apparatus, a main frame, a supplemental frame, a hollow sleeve forming a joint connection about which said frames are turnable, bearing wheels journaled upon the front and upon the rear frames respec-

tively, said wheels having internal gear teeth near the periphery, vertical shafts and sleeves turnable thereon, said sleeves carrying gear wheels which engage the teeth of the bearing wheels, transverse shafts with beveled gear connections to revolve the sleeves and gear wheels, a longitudinal countershaft passing through the sleeve connection of the frames having gears at opposite ends engaging gears upon the transverse wheel driving shafts, a motor located upon the main frame, and gearing whereby motion is transmitted therefrom to drive the countershaft.

6. In a traction apparatus, main and supplemental frames with independently turnable bearing wheels journaled thereto, said wheels having internal teeth, vertically turnable sleeves having gear wheels, the teeth of which engage those of the bearing wheels, clutch mechanisms carried by the gear wheels and adapted to interlock with the sleeves upon which the gear wheels are mounted to transmit motion to said gears in one direction, transverse shafts and beveled gears through which motion is transmitted to the vertical sleeves and a longitudinally journaled countershaft with gears connecting with the front and rear transverse wheel driving shafts, a motor, and connections through which power is transmitted to the countershaft, a reversing mechanism and reversing clutch devices connecting with the rear wheels whereby the apparatus may be caused to run in the opposite direction and the forward driving clutches disengaged.

7. In an apparatus of the character described, main and supplemental wheel frames, centrally journaled and turnable with relation to each other, gears and forwardly driven clutch mechanisms whereby motion is transmitted to revolve the wheels in a forward direction, a second clutch mechanism for each of the rear wheels adapted to drive said wheels in the reverse direction, means for disengaging the forwardly acting clutches and engaging the reversing clutches simultaneously, and reversible propelling mechanism.

8. In an apparatus of the character described, main and supplemental frames having a central longitudinal sleeve about which the frames are turnable with relation to each other, a driving shaft passing through said sleeves from front to rear, steering knuckles having horizontal bearing and driving wheels journaled thereon, said knuckles having vertical shafts at substantially right angles with the wheel bearing portion, sleeves turnable upon said shafts, gears carried upon said sleeves and engaging the internal gear teeth of the bearing wheels, a clutch mechanism whereby the gear wheels are engaged with the sleeves and propelled by such engagement to drive the bearing wheels, a transverse shaft, gears connecting the ends of the

shaft with the sleeves, other gears connecting the propeller shaft with the transverse shaft, and steering mechanism by which the wheels may be turned about the vertical shafts as a center of motion.

9. In an apparatus of the character described, the combination of main and supplemental frames, horizontal shafts having bearing wheels loosely turnable thereon, of steering knuckles having vertical shafts carried on the frames with turnable gear carrying sleeves through which motion is transmitted to drive the wheels, lever-arms connected with the steering knuckles and having a rigid connection between the front and rear steering knuckles, a turning mechanism comprising drums, flexible cables passing around the drums and connecting with the steering lever, and a wheel by which said drums are turned, and cables moved to turn the bearing wheels.

10. In an apparatus of the character described, main and supplemental frames turnably connected on a longitudinal central line, said frames having steering knuckles upon which front and rear bearing wheels are journaled, a motor carried upon the main frame, intermediate mechanism and gears through which the bearing wheels are propelled, a steering mechanism connected to turn the front wheels or the rear wheels simultaneously about the vertical portions of the steering knuckles, and a rigid connection

between the front and rear steering knuckles whereby the two may be turned in unison, 35 and a steering wheel and intermediate connections.

11. In an apparatus of the character described, independent front and rear frames having a central longitudinal connection 40 about which they are turnable, front and rear bearing wheels journaled upon the two frames and having internal teeth, gear wheels engaging the said teeth, clutch mechanisms by which said gear wheels are engaged with 45 driving sleeves upon which they are carried, oppositely arranged clutches connecting the sleeves of the rear wheels, a means by which said clutches are disengaged during the forward movement of the machine, means by 50 which the forward driving clutches of the rear wheels are disengaged and the rear driving clutches engaged, a motor and counter-shaft through which motion is transmitted to drive all the wheels in a forward direction, 55 and reversing gears whereby the reversing movement may be transmitted to the rear wheels when the forward driving clutches are disengaged.

In testimony whereof I have hereunto set 60 my hand in presence of two subscribing witnesses.
